UNITED STATES PATENT OFFICE.

MARTHE BRUELLE, OF BOIS COLOMBES, FRANCE.

DESIGN FOR A PERFUME VAPORIZER.

Application filed July 20, 1926. Serial No. 18,408. Term of patent 3½ years.

To all whom it may concern:

Be it known that I, MARTHE BRUELLE, a citizen of the Republic of France, residing at Bois Colombes, France, have invented a new, original, and ornamental Design for Perfume Vaporizers, of which the following is a specification, reference being had to the accompanying drawing, forming a part thereof.

In the drawings:

The figure is a side elevation of the perfume vaporizer as applied to a bottle or other container, the latter being shown in dotted lines.

I claim:

The ornamental design for a perfume vaporizer as shown.

BRUELLE, MARTHE.
